UNITED STATES PATENT OFFICE.

CURTIS S. CURRIER, OF PONTIAC, MICHIGAN.

TRAIN SIGNALING AND CONTROLLING SYSTEM.

1,190,520.

Specification of Letters Patent.

Patented July 11, 1916.

Application filed July 15, 1914. Serial No. 851,214.

To all whom it may concern:

Be it known that I, CURTIS S. CURRIER, citizen of the United States, residing at Pontiac, in the county of Oakland and State 5 of Michigan, have invented certain new and useful Improvements in Train Signaling and Controlling Systems, of which the following is a specification.

My invention relates to improved means 10 operating automatically to arrest the movement of one train should the same enter (from the rear) a block or track section already occupied by another.

As its primary object, the invention 15 contemplates means actuatable by a passing train to first signal and then position or set a semaphore arm or trip in such relation to the track as to engage and actuate suitable train carried control means should a second train, 20 having the said control means mounted thereon, enter, from the rear, the block or track section already occupied by the train acting upon or operating the said trip means.

25 The above and additional objects are accomplished by such means as are illustrated in their preferred embodiment in the accompanying drawings, described in the following specification and then more particularly 30 pointed out in the claims which are appended hereto and form a part of this application.

In describing my invention in detail reference will be had to the accompanying 35 drawings wherein like characters denote like or corresponding parts throughout the several views, and in which:—

Figure 1 is a plan view illustrating the 40 relative arrangement of the track obstacle and the train carried control means engageable therewith; Fig. 2 is an elevation, partly in section, of a portion of a locomotive showing the arrangement of the train carried control means mounted thereon; Fig. 3 is an 45 enlarged section of the operating valve; Fig. 4 is a horizontal section of the valve; Fig. 5 is a section of a second valve operable to control the steam supply; Fig. 6 is a section on the line 6—6 of Fig. 5; Fig. 7 is a

plan view of the element or block operable 50 to control movement of the trip means; Fig. 8 is a section on the line 8—8 of Fig. 7; Fig. 9 is a section on the line 9—9 of Fig. 8; Fig. 10 is a longitudinal sectional view of the means operable to actuate the trip device 55 and the signaling means; Fig. 11 is a similar view, the trip device and signaling means being in an operative position; Fig. 12 is an elevation of the trip operating means, the casing therefor being shown in section; Fig. 60 13 is an end view of the said operating means, the casing being in section; Fig. 14 is a fragmentary view illustrating the manner in which the switch devices or contacts are mounted; and Fig. 15 is a diagrammatic 65 view illustrating the several circuits necessary to operation of the controlling means.

Referring now to the drawings by numerals, 1 designates a track section, 2 a locomotive, 3 the train carried control means, and 70 4 the operating mechanism therefor, the said train carried control means and the said operating mechanism being each designated as an entirety.

Mounted upon the top of the locomotive 75 cab is a suitable rotary valve 5, the said valve consisting of a casing 6, valve 7 and operating shaft 8, the latter extending concentrically through the valve 7, and having mounted thereon, exteriorly of the casing, a 80 sleeve like support 9, within each end of which an arm 10 is fitted, the said arms being adjustable relatively to the support 9 to provide for their disposition in the path of the track obstacle or operating mechanism 4 85 to be hereinafter fully described. Support 9 is rigid with the shaft 8 and is adapted to turn the latter when actuated or engaged by the said operating means. The periphery of the valve 7 is cut away as indicated at 11, 90 that portion cut away being normally positioned out of registration or alignment with the branch terminals of an air pipe 12 leading into the valve casing.

An air outlet pipe 13 is open to the interior of the casing 6, the said outlet pipe being branched, the terminals of the branched portion being open to the valve interior at

points adjacent the extremities of the branch terminals of the inlet pipe 12, this arrangement causing the said valve member 7, when turned by actuation of support member 9, to align that portion cut away as at 11 with one of the inlet and outlet pipe terminals, this arrangement, as is apparent from the foregoing, providing a break in the air line and permitting, in a manner common to the art, a setting of the air brakes normally held inoperative by the compressed air within the pipe line of the train. If desired, manually operated means such as indicated at 14 may be provided for actuation of the valve.

15 A second valve, designated as an entirety by the numeral 15, disposed adjacent the steam dome 16 of the locomotive, and open to the steam pipe line 17 thereof, is also actuatable through movement of support member 9, the said valve 15 comprising a casing 18 into which sections of the pipe line 17 extend. A rotary valve member 19 is operable within the casing 18, said valve member being actuatable through movement of a lever 20 mounted exteriorly of the valve casing and connected to the valve by means of a stub shaft 21 extending into the casing and through the valve as shown to advantage in Fig. 5. Lever 20 is connected at each end to support member 9 through the medium of rods 22, such connection providing for a simultaneous operation of both the valve member 5 and the valve 15. Whistles 23 operate in conjunction with the valve 15, the whistles being blown automatically upon actuation of the valve, the latter, when actuated, causing a groove or passage way 24 formed therein to be swung out of alignment with the pipe line 17 into the position shown by the dotted lines in Fig. 6. As valve member 19 is turned or actuated, ports 25, disposed one upon each side of the groove or passage way 24 align steam pipe 17 with either one or the other of the pipes 26 leading to the whistles 23, the steam pressure within the line 17 causing the whistles, that is, one of them, to be blown, at the same time shutting off the steam supply necessary to the running of the locomotive.

50 Having described in detail the construction and operation of the train carried control means, I shall now proceed with a detail description of the construction and operation of the operating means therefor. The 55 said operating means, or track obstacle, consists of a semaphore blade or trip member 27 mounted upon a vertical shaft 28 in turn supported in a perpendicular or upright position by means of a tubular extension 29 forming a part of a casing or housing designated as an entirety by the numeral 30. Shaft 28 has mounted upon its lower extremity a spirally grooved block or element 31, the groove 32 of which is so formed or cut

as to impart to the shaft 28 a quarter turn 65 when raised or lowered in a manner to be hereinafter fully described. A pin 33, rigid with a cylindrical casing section 34 forming a part of housing 30, by reason of its engagement with the groove, will cause the 70 quarter turn above referred to to be put into effect upon movement of the shaft in the manner above set forth. A lug or projection 35, normally fitting a recess therefor in the base of cylindrical casing section 34, 75 serves as a means whereby member 31 is held against turning except when elevated sufficiently to disengage the lug and the recess.

Within housing 30 and as shown, within the base section 36 thereof, is arranged or 80 disposed the mechanism operable to raise and lower shaft 28, said mechanism consisting of a cam device 37 (flattened at one end) mounted eccentrically upon a shaft 38 journaled in uprights or brackets 39 arranged 85 within the housing. A roller 40 is engageable with the cam surface of cam device 37, the roller being mounted upon the lower extremity of a rod 41 operating within an opening therefor designated 42, of the housing, the opposite end of the rod from that supporting the roller 40 being directly engageable with the under side of block or element 31.

Cam device 37 is movable in one direction 95 by means of a gear 43 mounted upon shaft 38, the gear being normally in mesh with a bodily movable gear 44 carried by an arm 45 oscillatable about a shaft 46 journaled within the bracket 39 aforesaid. A leaf spring 100 47 exerts sufficient pressure upon arm 45 to normally hold gear 44 in mesh with gear 43, the former being movable out of mesh only upon actuation of cam device 37, an extension 48 of the cam by reason of its engagement with a lug 49 of the arm causing the said gear 44 to be bodily moved. Gear 44 is at all times in mesh with a third gear 50, the latter gear being mounted upon shaft 46, and driven directly by a motor 51 operable 110 within the housing as shown.

The above mechanism is actuatable to elevate rod 41 and accordingly block 31 and shaft 28. Mechanism in duplicate is arranged upon the opposite side of eccentric 115 37, said mechanism being controlled by a motor 52 and actuatable to reversely operate the eccentric and in this manner provide for a lowering of the rod 41, element 31, and shaft 28. A lug 53 projects laterally from 120 the cam device 37, the lug being engageable with support arm mounted upon the opposite side of the cam device from that upon which support arm 45 is mounted, this arrangement, as is apparent, causing one of the said 125 support arms to be actuated by the lug to swing movable gear out of mesh with operating gear, and projection or extension 48

causing the other of the said arms to move the other of the bodily movable gears out of mesh with the other of the said operating gears.

- 5 The numerals relating to the train of gears upon one side of the cam device have been applied to the train of gears upon the opposite side thereof, the said gears being, as above set forth, substantially in duplicate.
- 10 Passing on to the description of the means actuatable to render motors 51 and 52 operative and inoperative as occasion may demand, the numeral 54 designates a movable contact arranged inside and adjacent one of the rails of the track, the said contact being recessed or cut away as indicated at 55, a guide member 56 operating therein. A spring 57 is arranged to embrace the guide member 56, one end of the spring abutting the under side of the contact 54 and the opposite end the base or floor of a suitable housing 58 within which the contact, guide member and spring is arranged. The top face of the contact 54 is cut away at one end 25 as indicated at 59, that portion cut away, as illustrated to advantage in Fig. 9, causing the flange of a car wheel to move the said contact laterally without depressing the same against tension of spring 57. The opposite end of the contact 54 is shaped, as indicated at 60 in such a manner as to cause the said contact to be compressed against tension of the spring 57 upon the passage of a train over that portion of the track adjustment which the contact is disposed, the said contact when depressed, being adapted to close electrical circuits necessary to operation in a manner to be hereinafter fully set forth. As a means whereby lateral movement of contact 54 is limited, I provide a pin 61 operating within a slot 62 therefor within the casing 58. Four of these contacts are placed within each block or track section, two adjacent each of the respective block terminals. In the diagrammatic view, Fig. 15, the four contacts have been designated respectively *a*, *b*, *c* and *d*. Contact *a* is electrically connected with two of the motors designated *E* and *H*, and also with contact designated *d*. A train traveling in the direction indicated by the arrow in Fig. 15 will cause contact *a* to be depressed, thereby closing the circuit necessary to the operation of motors *E* and *H*, permitting the said motors to be actuated. Motors *E* and *H* will operate simultaneously upon the respective eccentrics or cam devices 37 and cause block elements 31 to be elevated from the position shown in Fig. 10 to the position shown in Fig. 11. A stationary contact 64 and a movable contact 65 are normally held in engagement, one with the other, by the said element 31 (the latter being in its lowermost position) thus permitting the circuit necessary to the operation 65 of the motors *E* and *H* to be complete. Electro-magnetic devices 66 and 67, when contacts *a* and *d* are depressed, will, by reason of the contacts 68 and 69 being in engagement one with the other, be energized, 70 thus holding the said contacts depressed until the elements 31 have been sufficiently raised to permit the said contacts 68 and 69 as well as 64 and 65 to be automatically disengaged by the spring arrangement designated 75 and illustrated to advantage in Fig. 14. Continued movement of the elements 31 will cause contacts 71 and 72 to be moved into engagement one with the other; contacts 73 and 74 to be moved into engagement one with the other, and contacts 75 and 76 to be moved into engagement one with the other; the former, 71 and 72 causing electro-magnetic devices 77 and 78 to be energized, the next, contacts 73 and 74 causing the circuit necessary to the operation of motors *F* and *G* to be closed and the said motors to be set in motion upon a depression of the contacts *b* and *c*; and finally, an incandescent lamp 79 carried by each shaft 28 80 to be lighted, the engagement between contacts 75 and 76 causing the lighting circuit to be closed, the said circuit above referred to remaining closed until the elements 31 are lowered by a closing of the circuit necessary 85 to operation of motors *F* and *G*. Continued movement of the train past contact *a* into engagement with contact *b* will cause the latter to be moved laterally without being depressed, the train continuing to move, 100 until in engagement with contact *c*, the latter being depressed to close the circuit necessary to operation of motors *F* and *G*. The motors *F* and *G* being set in motion, it is apparent that a reverse operation of the eccentrics 37 will be put into effect, such operation causing the element 31 to be lowered and the lamp or light 79 simultaneously extinguished and the electro-magnetic devices 77 and 78 to be simultaneously deenergized. 110
- It is thought unnecessary to refer to the conductors completing the several circuits by numerals or reference characters as the diagrammatic view, Fig. 15, is thought to clearly show the arrangement of the wires 115 and circuits necessary to the operation of the device.
- From the foregoing, taken in connection with the accompanying drawings it is apparent that a moving train will be signaled 120 first, and then automatically brought to a standstill should the said train enter (from the rear) a block or track section already occupied by another train; that the signaling devices and operating mechanism are 125 automatically rendered inoperative by the passage of the train from the block or track section of which the controlling means is a

part; and that where a control system constructed as above set forth is in use, accidents in the nature of rear end collisions and the like cannot take place so long as the controlling means remains intact.

Attention is also directed to the fact that the device or apparatus is, to a certain extent, automatic in preventing head on collisions in that the trainman upon the train 10 that has been brought to a stop at the exit of a block may run ahead and flag the train that is within the block and coming in his direction. If desired, the train brought to a stop at the exit of a block may, in view of 15 such automatic operation, back out of the block within which it has been stopped, into the preceding block, and thus set the signal within said latter block to stop the oncoming train.

20 In practice, I have found that the form of my invention, illustrated in the drawings and referred to in the above description, as the preferred embodiment, is the most efficient and practical; yet realizing that the 25 conditions concurrent with the adoption of my device will necessarily vary, I desire to emphasize the fact that various minor changes in details of construction, proportion and arrangement of parts may be 30 sorted to, when required, without sacrificing any of the advantages of my invention, as defined in the appended claims.

Having thus fully described my invention, what I claim as new and desire to 35 secure by Letters Patent, is:—

1. In combination with train carried control means, actuating means therefor including a trip arm movable into and out of operative position, a shaft upon which the 40 said arm is mounted, a spirally grooved block rigid with the said shaft, actuating means engageable with the said block and controlled through movement of a passing train to elevate the block, stationary means engageable with the groove in the block to 45 impart to the said arm a quarter turn simultaneously with the elevation of the block, and means controlled through movement of a passing train, said last mentioned means being actuatable to lower the said block and return the said arm to its normal inoperative position, as and for the purpose set forth.

2. In combination with train carried control means, actuating means therefor including a trip arm movable into and out of operative position, a shaft upon which the 55 said arm is mounted, a spirally grooved block rigid with the shaft, a pin stationary relatively to the block and fitting the groove therein, means operable to elevate the block, means actuatable by a passing train to control said operating means, independent means operable to lower the said block, and means actuatable by a passing train to con-

65 trol movement of said last mentioned operating means, as and for the purpose set forth.

3. In combination with train carried control means, actuating means therefor including a trip arm movable into and out of operative position, a shaft upon which the 70 said arm is mounted, a spirally grooved block rigid with the shaft, means stationary relatively to the block and fitting the said groove, to impart to the said arm a turning 75 movement when elevated through movement of said block, motor controlled means engageable with the said block to elevate the same, means actuatable by a passing train, said means being in electrical communication with the motor to control operation thereof, motor controlled means operable to lower the said block, and means actuatable 80 by a passing train in electrical communication with the said last mentioned motor, as 85 and for the purpose set forth.

4. In combination with train carried control means, actuating means therefor including a trip arm, a shaft upon which the said arm is mounted, means carried by the said 90 shaft for imparting thereto a quarter turn when actuated, motor control means including an eccentric operable to control movement of said shaft, means actuatable by a passing train, said means being in electrical communication with said motor control means, motor control means operable to 95 lower the said shaft, means actuatable by a passing train, said last mentioned means being in electrical communication with said last mentioned motor control means, as and for the purpose set forth.

5. In combination with train carried control means, actuating means therefor including a trip arm movable into and out of operative position, a shaft upon which the 100 said arm is mounted, a spirally grooved block mounted upon the said shaft, a pin stationary relatively to the block and fitting the groove to impart to the said arm a turning movement when actuated, an eccentric actuatable to raise and lower the said block, motor control means operable to actuate the eccentric for elevating the said block, motor control means operable to actuate the eccentric to lower the said block, and means actuatable by a passing train to control operation 105 of said motor control means, as and for the purpose set forth.

6. In combination with train carried control means, actuating means therefor including a trip arm movable into and out of operative position, a shaft upon which the 110 said arm is mounted, means mounted upon the said shaft, said means being actuatable 115 upon movement of the said shaft to impart to the arm a turning movement, an eccentric actuatable to raise and lower the said shaft,

a shaft upon which the said eccentric is mounted, means mounted upon the said shaft, said means being actuatable to move the eccentric in one direction and cause the 5 said trip arm to be elevated, means mounted upon the said shaft, said means being actuatable to move the eccentric in the opposite direction and cause said trip arm to be lowered, means actuatable by a passing train to 10 control movement of the said first mentioned

operating means, and means actuatable by a passing train to control movement of said last mentioned operating means, as and for the purpose set forth.

In testimony whereof I affix my signature 15 in presence of two witnesses.

CURTIS S. CURRIER.
